UNITED STATES PATENT OFFICE.

GEORGE H. WOOD, OF WEST PHILADELPHIA, PENNSYLVANIA.

SAW SHARPENER.

Application filed April 13, 1926, Serial No. 101,749.

This invention relates to saw sharpeners and more particularly to a hand operated device adapted to sharpen a plurality of teeth at a single operation.

5 An important object of the invention is the provision in a structure of this character of means for simultaneously supporting a plurality of saw files in parallel relation of such character that the saw files may be canted to 10 present an angle thereof to the teeth of the saw in any desired position.

A further object of the invention is to provide a frame having means for holding saw files in this manner and having further 15 means whereby the angle of the files with relation to the longitudinal axis of the frame may be altered while maintaining the parallelism and rotated adjustment thereof.

A still further object of the invention is to 20 provide a device of this character in which the adjustments may be very readily accomplished, which may be readily and durably constructed and which will be a general improvement in the art.

25 These and other objects I attain by the construction shown in the accompanying drawings, wherein for the purpose of illustration is shown a preferred embodiment of my invention and wherein:—

30 Figure 1 is a plan view of saw filing apparatus constructed in accordance with my invention, the files being illustrated as canted in dotted lines;

35 Figure 2 is a section on the line 2—2 of Figure 1;

Figure 3 is a longitudinal sectional view;

Figure 4 is a combined perspective of the tilting mechanism;

40 Figures 5 and 6 are enlarged fragmentary detail views showing the operation of the tilting mechanism and illustrating two extreme positions of the file;

Figure 7 is a section on the line 7—7 of Figure 1.

45 Referring now more particularly to the drawings, the numeral 10 generally designates a rectangular frame, one of the end members 11 and 12 of which is removably mounted and adjustable longitudinally of 50 the frame. In the present instance, the side members 13 of the frame and the end member 11 are disclosed as having opposed ears 14 and 15 for coaction with clamping screws

16. The end member 11 has projecting webs 17 operating in slots 18 formed in the side 55 members to guide the end member in its movements. Each end member has attached thereto a handle 19. The end members 11 and 12 have their inner faces channeled and in the channel of the end member 11 is slidably mounted a plate 20 having openings 21 for the reception of the tip or smaller ends of files F. As more clearly shown in Figure 3, these openings increase in diameter toward the outer face of the plate. The end 60 member and the adjacent portion of the handle 19 are channeled in alignment with these openings, as indicated at 22, so that the tips of the files may extend thereinto. The plate 20 is adjustable transversely of the end member 65 in its channel and is held in adjusted positions by a spring-pressed and supported pin 23 extending through the upper wall of the channel and into a selected one of a series of openings 24 formed in the edge of the 70 plate.

In the channel of the end member 12 is arranged an assembly consisting of inner and outer plates 25 and 26 held in spaced relation at their corners by blocks 27 and at their lower edges by a strip 28, the upper edge of which is provided with obtusely angular notches 29. Slidable between the plates is an oscillating bar 30, the lower edge of which slides upon the upper face of the bar 28 and the ends of which extend between the blocks 27. The plate is formed to provide shoulders 31 which will engage the upper blocks 27 and limit sliding movement of the oscillating bar. This oscillating bar has in its lower 80 face notches 32 corresponding in number and arrangement with the notches 29 and coacting therewith to receive the tang ends of files F. By shifting the bar 30 to the right or to the left, the angular position of the file may 85 be rotatably adjusted as will be obvious by an inspection of Figures 5 and 6. Means are provided to permit this adjustment comprising a spindle 33 journaled in the plates 25 and 26 and having secured thereto a pinion 34 in alignment with the oscillating bar 30 and coacting with a rack 35 formed in the upper surface thereof. The inner end of this spindle projects inwardly of the inner plate and has secured thereto a milled operating 90 head 36. The plate 26 in alignment with the

notches 29 of the bar 28 has formed therein openings 37 for the passage of the files in which the files may rotate freely. The walls of the notches flare toward the outer face of the bars 28 and 30 so that the file is gripped and yet at the same time may be canted, as indicated in Figure 1. The plate 25 has a slot 38 permitting passage of the tangs of the files while preventing passage of the butt or larger ends thereof.

In the use of the device, files are inserted thereto by adjusting the end member 11 outwardly or entirely removing the same and inserting the tang ends of the files through the openings 37 and notches 28. The tips of the files are then engaged in the openings 21 and the end member 11 adjusted to its proper position. The files will then be held in parallel relation and may be rotatably adjusted to obtain the proper angle of the cutting face of the file by rotating the milled head 36 which preferably has indicia coacting with a fixed indicator upon the frame to show the position in which the files are disposed. If it is desired, as many operators desire, that the files be arranged at an angle to the frame, this may be accomplished by adjusting the plate 20 until the desired angle is attained.

Since it is obvious that the structure hereinbefore set forth is capable of a certain range of change and modification without materially departing from the spirit of the invention, I do not limit myself to such specific structure except as hereinafter claimed.

Having described the invention, I claim:

1. A saw sharpening device comprising a metal frame designed to hold any desired number of files between the ends thereof, means at one end of the frame for simultaneously shifting the corresponding ends of all the files to thereby dispose the files angularly with respect to the longitudinal plane of the frame and means for simultaneously canting the files while held within the frame.

45 2. A saw filing apparatus comprising a frame, designed to receive any desired number of equidistantly spaced cross sectionally V-shaped saw files between the ends thereof, means for adjusting one of the ends with respect to the body of the frame for clamping the files on the frame, means for moving the files simultaneously in either direction on one end of the frame and arranging said files angularly with respect to the longitudinal plane of the frame and means on the second end of the frame for simultaneously canting the files.

60 3. A saw filing apparatus, comprising a metal frame having handles on the ends thereof, and one of said ends being adjustable with respect to the frame proper, guide means between said end and the sides of the frame proper, said ends designed for engagement with cross sectionally V-shaped files which are equidistantly spaced and which are held

on the frame by the adjustment of the movable end with respect to the body of the frame, means on one of the ends of the frame for bodily moving all of the files to determined positions in the frame, whereby to hold said files at desired or determined angles with respect to the longitudinal plane of the frame, means on the second end of the frame for canting the files and means for locking said canting means.

75 4. A saw filing apparatus comprising a metal frame having handles extending from the ends thereof and one of the ends adjustable with respect to the sides of the frame proper and the said sides being of a less thickness than the ends, said ends having their inner faces channeled and being provided with elongated slots there-through, an apertured block received in one of the channeled ends and designed to receive the ends of equidistantly spaced cross sectionally V-shaped files in the apertures thereof and which ends may project through the opening in the end of the frame, means for sliding the block on the end for determined distances to arrange the files angularly with respect to the longitudinal plane of the frame, means for locking the block from such movement, a casing in the channeled portion of the second V-shaped notches in the casing, a slideable plate in the casing arranged over the block, said slideable plate having notches disposed opposite the notches in the bar and the inner corners provided by the notches having V-shaped depressions, said slideable plate having a rack surface, a toothed wheel engageable therewith, a headed operating member for the toothed wheel arranged exteriorly of the casing, the outer element of the casing having an elongated slot therethrough in a line with the notches, the inner member of the casing having apertures therethrough and in a line with the notches and with the slot in the said end of the frame and said slots and notches designed to receive the second cross sectionally V-shaped ends of files therethrough, as and for the purpose set forth.

100 5. A saw sharpening device comprising a frame having at opposite ends thereof means for receiving and holding the ends of parallel files, said means at one end of the frame being bodily adjustable with its engaged file ends transversely of the frame, the means at the opposite end of the frame being adjustable to simultaneously oscillate files engaged therewith about their axes.

105 6. A saw sharpening device comprising a frame having at one end thereof means to rotatably receive corresponding ends of a group of files and means at the opposite end thereof receiving the files to maintain them in parallel relation, the last named means including relatively movable plates shiftable while the files are engaged therewith to oscillate the files about their axes.

7. A saw sharpening device comprising a frame having at one end thereof means to rotatably receive corresponding ends of a group of files and means at the opposite end thereof receiving the files to maintain them in parallel relation, the last named means including relatively movable plates shiftable

while the files are engaged therewith to oscillate the files about their axes, the first named means being bodily adjustable transversely 10 of the frame to thereby vary the angle of the saws to the frame.

In testimony whereof I affix my signature.

GEORGE H. WOOD.
